To all whom it may concern:

Be it known that I, NICHOLAS WITSCH, a citizen of the United States, residing at Jersey City, in the county of Hudson and State of New Jersey, have invented and produced a new and original Design for an Ornamental Print or Pattern for Cigar-Boxes; and I do hereby declare the following to be a full, clear, and exact description of the same, reference being had to the accompanying drawing, forming a part thereof.

tral figure and having a festooned ribbon in background which extends across from side to side under said central figure; also two escutcheoned shields arranged one upon each side of and partly above said central figure, from each of which shield extends a streamer.

I claim—
